Harold Van Doren and Donald Dailey, Toledo,
and George M. Geiger, Mount Gilead, Ohio, as-
signors to The Hydraulic Development Corpo-
ration, Inc., Wilmington, Del., a corporation
of Delaware

Application October 30, 1939, Serial No. 87,946

Term of patent 14 years

To all whom it may concern:

Be it known that we, Harold Van Doren and
Donald Dailey, residing at Toledo, in the county
of Lucas and State of Ohio, and George M.
Geiger, residing at Mount Gilead, in the county
of Morrow and State of Ohio, all being citizens
of the United States, have invented a new,
original, and ornamental Design for a Gear
Pump, of which the following is a specification,
reference being had to the accompanying draw-
ing, forming a part thereof.

In the drawing:

Figure 1 is a perspective view taken from the

front and side of a gear pump showing our new
design;

Figure 2 is a plan view thereof;

Figure 3 is a rear elevation thereof;

Figure 4 is a front elevation thereof; and

Figure 5 is a side elevation thereof.

We claim:

The ornamental design for a gear pump, as
shown.
